UNITED STATES PATENT OFFICE

HANS BELLER, OF LUDWIGSHAFEN-ON-THE-RHINE, AND HERMANN SCHUETTE, OF MANNHEIM, GERMANY, ASSIGNEES TO I. G. FARBENINDUSTRIE AKTIENGESELLSCHAFT, OF FRANKFORT-ON-THE-MAIN, GERMANY

PRODUCTION OF ASSISTANTS FOR THE TEXTILE AND RELATED INDUSTRIES

No Drawing. Application filed June 15, 1931, Serial No. 544,696, and in Germany June 28, 1930.

The present invention relates to the production of assistants for the textile and related industries and particularly of wetting, cleansing and emulsifying agents.

5 A process for the production of wetting, cleansing and emulsifying agents has been elsewhere described according to which high molecular aliphatic olefines having a double linkage at the end of a chain of at least 8 carbon atoms, such as may be obtained for example from the corresponding monohydric aliphatic alcohols by splitting off water, are sulphonated under energetic conditions.

We have now found that equally valuable 15 products which may be employed in an advantageous manner as wetting, cleansing and emulsifying agents can be obtained by treating the olefinic mixtures obtainable from the oxidation products of a destructive oxidation 20 of difficultly volatile, liquid or solid aliphatic hydrocarbons, i. e. aliphatic open chain or cycloaliphatic hydrocarbons, containing at least 8 carbon atoms and mixtures containing a preponderating quantity of such hydrocarbons, or mixtures containing a preponderating 25 quantity of the said olefines, with energetic sulphonating agents, such as oleum, chlorsulphonic acid or sulphur trioxide, or with less energetic sulphonating agents such as concentrated sulphuric acid, under energetic 30 conditions, i. e. at temperatures above 100° C. or while removing the water formed by means of dehydrating agents, such as acetic anhydride and/or by an extended period of working, until true sulphonic acids 35 ($\equiv C-SO_2OH$) are formed. This aim is attained as soon as a sample remains soluble in water after boiling with an aqueous about 10 per cent hydrochloric acid solution.

40 The olefines employed as initial materials may be of aliphatic, cycloaliphatic or aliphatic-cycloaliphatic nature and usually contain olefines with one double linkage in the molecule in preponderating quantities; they 45 may be obtained for example according to the process described in the application Ser. No. 478,550 filed by one of the present inventors together with another on August 28, 1930. Moreover, mixtures of olefines may be em- 50 ployed which contain olefinic compounds con-

taining hydroxy, carboxylic acid or carboxylic ester groups besides the double linkages. Since the hydroxyl groups of the constituents of the oxidation products are mainly contained in or near the centre of the chains, 55 the double linkages will not be in a final position of at least 50 per cent, or generally more, of the olefinic constituents.

Such olefines, or mixtures containing them, can be obtained for example from the products of a destructive oxidation of liquid or solid paraffin or naphthene hydrocarbons, as for example paraffin oil or wax, petroleums, benzines, middle oils, brown coal tar oils, Montan wax or other waxes, hydrogenation 60 products of coals or tars, petroleums and the like. These oxidation products, which contain hydroxy, carboxylic or ester groups or several of such groups as for example in hydroxy-carboxylic acids, estolides, lactides 65 or lactones are subjected to distillation whereby double linkages are formed in the molecule while water is split off. As a rule, a splitting off of carboxylic and ester groups, when such are present, also takes place during 70 this distillation. The olefines employed for the sulphonation may be solid or liquid and may be employed in admixture with high molecular organic compounds containing more than 8 carbon atoms such as alcohols, 75 carboxylic acids, hydroxy-carboxylic acids or esters of any origin. The single olefines as such, separated for example by distillation, or in admixture with each other, or the whole of the mixture containing olefines or fractions 80 of the same may be subject to the sulphonation.

The sulphonation of the olefines is preferably effected while employing energetic sulphonating agents, as for example chlorsulphonic acid, oleum or sulphur trioxide, or concentrated sulphuric acid either at temperatures above 100° C. or in the presence of a dehydrating agent. It is often preferable in any case to employ additions of dehydrating agents, such as phosphoric anhydride, acetic anhydride, acetyl chloride and the like, or superficially active catalysts, as for example active carbon or diatomaceous earth during the sulphonation. Solvents or 85 90 95 100

diluents such as chloroform, trichlorethylene, nitro-benzene, diethyl ether and the like may also be present during the sulphonation. In this manner, true sulphonic acids are obtained, that is compounds which when boiled with dilute aqueous mineral acids do not decompose with the splitting off of sulphuric acid. The conditions of the sulphonation may also be selected so that a mixture of true 10 sulphonic acids and sulphuric esters is obtained, for example a temperature of about 40° C. may be applied when working with oleum.

According to this invention, water-soluble 15 sulphonic acids, or mixtures thereof with sulphuric esters, are obtained which may be employed as such or in the form of their inorganic or organic salts as assistants in the textile, leather or paper industries, and in the 20 production of polishing and cleansing preparations and, generally, as wetting, emulsifying and cleansing agents. The said sulphonic acid compounds may be employed in acid, alkaline and neutral media and are 25 especially suitable as wetting, cleansing and washing agents for textiles of all kinds and for raw fibres, for the preparation of dispersions, i. e. solutions, suspensions or emulsions, 30 of solid or liquid substances, as for example dye-baths, dyestuff pastes, dyestuff powders, oils, fats, waxes, paraffins, organic solvents and other insoluble substances, especially in water, and as additions to mercerizing liquors, 35 carbonizing baths, liquids to be employed for dressing, and as softening agents and the like. The products may be employed alone or in admixture with other substances, such as inorganic or organic salts, soaps or the so-called substitutes for soaps as for example 40 saponin, Turkey red oils, or sulphonic acids of aromatic mono- or especially poly-nuclear compounds, further with glue, gelatines, gum arabic, vegetable mucilages or solvents. The 45 sulphonic acids may also be employed for the preparation of drilling and lubricating oils, and as agents for working up leather and metal polishes.

The following examples will further illustrate the nature of this invention, but the 50 invention is not restricted to these examples. The parts are by weight.

Example 1

45 parts of chlorsulphonic acid are stirred 55 at from about 30° to 40° C. into 100 parts of a liquid mixture of olefines, obtained from the fraction of an oxidation product of hard paraffin wax, insoluble in petroleum ether, by splitting off water and carbon dioxide by 60 destructive distillation, and having an iodine value of over 100. The whole is then stirred at room temperature until the product has become soluble in water. Any hydrochloric acid gas still present is expelled by blowing 65 air through the reaction mixture, the mixture

is poured on to ice and the remainders of sulphonating agent are removed by washing with a 10 per cent aqueous solution of Gluber's salt. After neutralizing with an aqueous dilute solution of an alkali, such as alkali metal hydroxide, ammonia or organic amines, such as mono-, di-, or triethanol amine, cyclohexyl ethanol amines or pyridine and the like, a solution is obtained which may be employed as such as washing or emulsifying agent as well as the salts of the sulphonic acid which are obtained in a solid form by evaporating the solution. The resulting products have an excellent washing and emulsifying power. The sulphonic acids obtained 80 cannot be saponified by boiling with aqueous mineral acid.

Example 2

Russian gas oil is oxidized with air at about 160° C. in the presence of a small quantity of manganese naphthenate until the oil has a saponification value of 170 and is then distilled in vacuo at 12 millimetres mercury gauge. The saponifiable constituents are 85 first separated from the distillate by saponification with alkalies, and then the unsaturated hydrocarbons are separated from the unsaponifiable fraction in the usual manner, as for example by distillation. 100 parts of the olefines thus obtained are converted into true sulphonic acids by warming them with a mixture of 30 parts of acetic anhydride and 30 parts of sulphuric acid monohydrate 90 at about 35° C. After the reaction mixture 100 has become soluble in water, which is the case after from about 5 to 6 hours, ice is added to the reaction mixture; it is then diluted with water and neutralized with alkaline substances as described in Example 1. A product having an excellent washing action is obtained. The sulphonic acids obtained cannot be saponified by boiling with aqueous mineral acid.

Example 3

Soft paraffin wax is oxidized by blowing with air at 160° C. for 6 hours and the acid constituents are removed from the oxidation product by washing with about 25 per cent aqueous caustic soda solution. The unsaponifiable constituents are separated by centrifuging at about 20° C. into a liquid fraction 110 consisting mainly of substances containing hydroxyl groups and a solid fraction mainly consisting of unattacked initial paraffin wax. 115 The liquid fraction is heated to from 180 to 220° C. with a few per cent its weight of agents removing water, such as zinc chloride, concentrated sulphuric acid and the like acting agents, whereby mainly olefines are obtained in addition to unchanged hydroxyl compounds.

100 parts of the mixture thus obtained are vigorously stirred at 15° C. with 80 parts of 120 oleum containing 23 per cent of sulphur tri-

oxide. The temperature is then raised to from 25° to 30° C. and the mixture stirred for about 5 hours until a sample withdrawn is soluble in water. The reaction mixture is then poured on to ice and neutralized with caustic soda solution. The product has excellent washing and emulsifying properties. The sulphonic acids obtained cannot be saponified by boiling with aqueous mineral acid.

10 What we claim is:—

1. The process for the production of assistants for the textile and related industries which comprises acting with a sulphonating agent on olefinic mixtures, resulting from splitting off at least water from products of the liquid phase oxidation of difficultly volatile, aliphatic hydrocarbons, under such energetic reaction conditions as regards strength of sulphonating agent, reaction temperature and presence of dehydrating agents that a sample of the reaction product remains soluble in water after boiling with aqueous hydrochloric acid.

2. As new articles of manufacture assistants for the textile and related industries comprising sulphonic acid compounds of olefinic compound resulting from splitting off at least water from the hydroxyl- and carboxyl-bearing products of the liquid phase oxidation of difficultly volatile, aliphatic hydrocarbons.

3. As new articles of manufacture assistants for the textile and related industries comprising sulphonic acid compounds of mixtures of olefines and other olefinic compounds resulting from plitting off at least water from the hydroxyl- and carboxyl-bearing products of the liquid phase oxidation of difficultly volatile aliphatic hydrocarbons.

4. As new articles of manufacture assistants for the textile and related industries comprising sulphonic acid compounds of olefines, resulting from plitting off at least water from the hydroxyl- and carboxyl-bearing products of the liquid phase oxidation of difficultly volatile aliphatic hydrocarbons, and sulphuric esters from said olefines.

5. As new articles of manufacture assistants for the textile and related industries comprising alkali salts of sulphonic acid compounds of olefines, resulting from splitting off at least water from the hydroxyl- and carboxyl-bearing products of the liquid phase oxidation of difficultly volatile aliphatic hydrocarbons.

55 6. As new articles of manufacture assistants for the textile and related industries comprising sulphonic acid compounds of olefines, resulting from splitting off at least water from the hydroxyl- and carboxyl-bearing products of the liquid phase oxidation of a mineral middle oil.

7. As new articles of manufacture assistants for the textile and related industries comprising sulphonic acid compounds of olefines, resulting from splitting off at least

water from the hydroxyl- and carboxyl-bearing products of the liquid phase oxidation of a mineral middle oil and sulphuric esters from said olefines.

8. As new articles of manufacture assistants for the textile and related industries comprising alkali salts of sulphonic acid compounds of olefines, resulting from splitting off at least water from the hydroxyl- and carboxyl-bearing products of the liquid phase oxidation of a mineral middle oil.

9. As new articles of manufacture assistants for the textile and related industries comprising sulphonic acid compounds of olefines, resulting from splitting off at least water from the hydroxyl- and carboxyl-bearing products of the liquid phase oxidation of soft paraffin wax.

10. As new articles of manufacture assistants for the textile and related industries comprising alkali salts of sulphonic acid compounds of olefines, resulting from splitting off at least water from the hydroxyl- and carboxyl-bearing products of the liquid phase oxidation of soft paraffin wax.

In testimony whereof we have hereunto set our hands.
